UNITED STATES PATENT OFFICE

MICHAEL NICOLETTI, OF NORTH ATTLEBORO, MASSACHUSETTS

ORNAMENTAL METAL FABRIC

Application filed October 3, 1928. Serial No. 310,077.

The present invention relates to ornamental fabric which may be used for an unlimited number of purposes, the fabric being constructed of metallic units arranged in such close association with each other as to afford the fabric a practical solid appearance, yet connected together in a manner that renders the fabric exceedingly flexible.

The nature and advantages of the invention 10 will be better understood when the following detail description is read in connection with the accompanying drawings, the invention residing in the construction, combination and arrangement of parts as claimed.

15 In the drawings forming part of this application like numerals of reference indicate corresponding parts in the several views, and wherein:

Fig. 1 is a plan view of a portion of a fabric constructed in accordance with one embodiment of the invention;

Fig. 2 is a fragmentary enlarged view of the same;

Fig. 3 is a detail view of one of the metallic units;

Fig. 4 is a sectional view on line 4—4 of Fig. 2;

Fig. 5 is a view similar to Fig. 1 of a modified form of the invention;

30 Fig. 6 is an enlarged fragmentary plan view of the same;

Fig. 7 is a detail view of one of the metallic units used in the modified form of the invention;

35 Fig. 8 is a plan view of a still further modified form of the invention;

Fig. 9 is a detail view of one of the metallic units embodied in the structure shown in Fig. 8;

40 Fig. 10 is a view similar to Fig. 4, but shows the extensions bent in looped formation;

Fig. 11 is a view of a unit with four extensions, one projecting from each side and end, 45 with the extensions bent in confronting relation with respect to the unit;

Fig. 12 is a view of the form of the invention as shown in Fig. 11, with the extensions in their position prior to being bent;

50 Fig. 13 is a view showing a unit of the type

as illustrated in Fig. 7 but with only three extensions formed therewith; and

Fig. 14 is a view of a still further modified form of my invention.

In Figs. 1 to 4 inclusive I have illustrated 55 one embodiment of the invention, wherein the fabric is composed of a plurality of metallic units 10, each being preferably of bottle formation in outline although substantially flat. Consequently each unit includes a body portion 60

of any desired dimension and a reduced neck portion the opposite sides of which are curved as at 11 so that the various units can be very closely associated as illustrated in

Fig. 1, thereby affording the fabric the appearance of a solid piece of metal. However, the various units are connected together in a novel manner which allows any particular unit or units to be replaced when the occasion 65

requires, the connecting means for the various units also affording the fabric a very high degree of flexibility. The body portion of each unit is preferably rounded at its edges, so that when the units are arranged side by

side the reduced neck portion of the units of one row are arranged between the units of the next adjacent row, with the curved edges of the body portions of the last-mentioned units engaging the curved edges 11 of the units received therebetween. This arrangement is 70

clearly illustrated in Fig. 1, wherein it will be noted that the units in the row indicated at A are equidistantly spaced apart, while the units in the next adjacent row B are arranged alternately with respect to the units in the 75

row A, that is having neck portions arranged between the last-mentioned units as illustrated.

Consequently the units of all the rows are allowed to contact each other and this close 80 association of the various units gives the fabric the appearance of a solid piece of metal, yet the fabric in its entirety is very flexible due to the peculiar connection between all of said units.

85 In accordance with the invention illustrated in Figs. 1 to 4 inclusive, the unit 10 is provided with laterally disposed extensions 12 which project from the opposite sides of the unit, with an additional extension pro- 90

jecting from the neck portion thereof as clearly shown in Fig. 3, while Figs. 11 and 12 show an additional extension indicated by the reference numeral 13' and formed with the 5 large end of the unit. All of these extensions are bendable so that they can be bent upon themselves to form eyes 14 in Fig. 4, or they can be bent to lie in parallelism with the unit as shown in Figs. 10 and 11, and when 10 so bent provide loops 14'. Rings 15 are used in connection with the eyes 14 and loops 14' to connect the units together in sheet formation, each ring connecting the adjacent units of each row with one of the adjacent units 15 of the next row. As shown in Figs. 1 and 2, the units are provided with only three extensions and the rings 15 are arranged between the units of each row and are received by the eyes 14 of the adjacent units of said row, 20 while other rings are also received by the eyes formed by the extensions 13 that project from the neck portions of the adjacent units of the next row illustrated. The rings that secure the extensions 12 of adjacent units together 25 not only receive the extensions 13 in the form of the invention as illustrated in Fig. 12, but will also receive the extensions 13', and in this event the large ends of the units will be attached to the adjacent units. This arrangement holds all of the units of the fabric closely associated, and at the same time affords the fabric maximum flexibility.

In Figs. 5 to 7 inclusive, I have illustrated a modified form of the invention which varies from the form above described merely in the contour of the metallic units 16. Each of these units is substantially diamond-shape in plan, with each corner cut away to provide a concaved or curved edge 17 for a purpose to 35 be presently described. Projecting from each of these curved edges or corners of each unit is a bendable extension 18 adapted to be bent upon themselves to form looped eyes similar to those illustrated at 14 in Fig. 4. 40 The units are all arranged side by side with the units of one row being disposed alternately in staggered relation with the units of the next adjacent row, all of said units being connected together by rings 19 in the same 45 manner as described in the preferred embodiment of the invention. The concaved edges or cutaway portions 17 of each unit receives the adjacent ring 19, so that when all the 50 units are connected together each ring is surrounded by the adjacent group of units 16 so that the rings lie in the same plane as said units to afford the fabric the appearance of a solid piece of metal. All of the rings are free 55 to turn in the concaved edges, while the connection described affords the fabric a high 60 degree of flexibility.

In Figs. 8 and 9 I have illustrated a further modification of the invention wherein the metallic units are substantially crescent-shaped and indicated at 20. These units are

arranged side by side as clearly illustrated in Fig. 8, and are also connected together by rings 21. Each unit 20 is formed at its ends with bendable projections 22, while projecting from the opposed sides of each unit are similar bendable projections 23, the projections 22 of each unit being adapted to be bent upon themselves to form eyes to receive the rings 21 supported by the next adjacent unit by means of the bendable projections 23 which are also bent to form eyes or loops to receive said rings.

In Fig. 13 I have illustrated a unit of the shape as shown in Fig. 7, but it will be noted that one of the ends is formed without an extension 18, and this unit can be used at the 75 edges of the fabric.

The modified form of the invention as shown in Fig. 14 includes a unit 24 that is substantially square in formation with concaved corners 25, and projecting centrally from each corner is an extension 26 which is bendable in loop or eye formation for receiving rings to secure the units of this form together in fabric formation in the manner as shown in Figs. 1, 2, 5 and 6.

While it is believed that from the foregoing description the nature and advantages of the invention will be readily apparent, I desire to have it understood that I do not limit myself to what is herein illustrated and described and that such changes may be resorted to when desired as fall within the scope of what is claimed.

What I claim is:

1. An ornamental fabric composed of a plurality of metallic units arranged in superimposed rows, with the units of each row being spaced apart to receive the units of the next adjacent row and all of said units disposed in contacting engagement to afford the fabric the appearance of a solid piece of material, and means for connecting the units of the respective rows together in a manner to afford the fabric a high degree of flexibility.

2. An ornamental fabric comprising a plurality of similarly constructed metallic units arranged in spaced rows, with the units of one row arranged in staggered relation with respect to the units of the adjacent row and received between the latter for disposal in contacting engagement therewith, bendable extensions projecting from each unit and adapted to be bent upon themselves to form ring-receiving means, and rings received by said means in a manner for holding the units together and to afford the fabric a high degree of flexibility.

In testimony whereof I affix my signature.

MICHAEL NICOLETTI.
